ELECTRIC SHAVING IMPLEMENT

James D. Altemus, Roslyn, N. Y.

Application January 7, 1938; Serial No. 183,755

1 Claim. (Cl. 30—43)

This invention relates to electrical shaving implements of the type commonly known as dry shavers and has for its particular objects the provision of an implement of that character in which the movable shearing element or blade member and the cooperating shearing edges of the stationary head are so disposed that the cutting edges thereof are exposed so as to intimately contact with the skin while at the same time the relation between such blade element and the associated cutter members is such that it is impossible for the skin to enter therebetween and become cut during a shaving operation, while at the same time the reception of hairs between the cutting element and the associate cutting members is facilitated. Still other objects of the invention are the provision of a blade element which is relatively inexpensive and which may also, if desired, be renewed or replaced at will when the edges thereof become dull. Other objects of the invention are the provision of an implement which is attractive in appearance, extremely compact, sturdy and in which the edges of the cutting element and members are capable of long service without requiring their resharpening.

In the accompanying drawings in which I have illustrated preferred forms of my invention—

Figure 1 is a perspective view of my improved shaving implement;

Fig. 2 is a fragmentary vertical, transverse section of the implement shown in Fig. 1;

Fig. 3 is a plan view and Fig. 4 is a front elevation of the cutter head of the implement isolated from the holder;

Fig. 5 is a perspective view of the cutter element in the form wherein the same is not renewable by the user;

Fig. 6 is a perspective view showing the opposing cutter members which co-operate with such cutter element;

Fig. 7 is a perspective view of a modified form of cutter element which is of the renewable type;

Fig. 8 is a fragmentary, central, vertical section of the shaving head of a modified form of my invention;

Fig. 9 is a central, vertical section of a razor embodying a still further modification, but partly in elevation and showing but a fragment of the handle member;

Fig. 10 is a plan view of the razor construction shown in Fig. 9;

Fig. 11 is a longitudinal, vertical section on the line 11—11 of Fig. 10;

Fig. 12 is a transverse, vertical section on the line 12—12 of Fig. 10;

Fig. 13 is a bottom plan view of the blade carrier, isolated; and

Fig. 14 is a bottom plan view of the blade, isolated.

5 Referring to the drawings and the construction shown therein, the reference numeral 1 designates a holder or handle which includes an electric motor housed therein (not shown) and 2 the main shaft of the implement which is adapted to be driven by such electric motor in an anti-clockwise direction when viewed from the top of the implement. A knurled thumb wheel 3 admits of initially manually spinning the shaft 2 when the motor circuit is first closed, thereby 10 serving in the well known manner as a starter for the motor.

In the top of the holder is mounted a shaving head, the same comprising two members 5 and 6 respectively, the former having an obliquely extending hollow-ground shearing member 7 and the latter having an opposing obliquely extending hollow-ground shearing member 8 integrally formed thereon. The opposing members of the said head are adapted to be fitted together in the manner shown in Figs. 2 and 4, said cutter member 5 being provided with apertures a, which are adapted to receive corresponding projecting pins b, rigidly fixed or fitted in the member 6. Said cutter member 5 is also provided with tapped apertures c, which are so disposed as to register with drilled apertures d formed in the cutter member 6, when the two are assembled as shown in Fig. 2, so as to permit of screws 9 being inserted through the apertures d and being threaded into apertures c, thus securely locking said members 5 and 6 together. A set screw 10, which has a knurled head 11, and a curvilinear inner end which is adapted to enter a concave recess 12 formed in the shank 13 of the member 6, serves to locate and rigidly secure the shaving head in its proper position in the handle. The members 5 and 6 are also provided with semi-circular grooves 15 and 16, respectively, which are adapted to embrace and serve as guides for the aforesaid shaft 2 when said shaving head is mounted in said handle as indicated in Fig. 2.

40 A reciprocating cutter bar 20 is slidably mounted between said members 5 and 6, the same being adapted to reciprocate in the axial slot 22 formed between the respective members 5 and 6. As shown in the construction illustrated in Fig. 5, said cutter bar has an upwardly projecting obliquely extending hollow-ground double-edged blade element 23 integrally formed thereon, which 45 blade reciprocates longitudinally in the oblique

50 slot 22. A reciprocating cutter bar 20 is slidably mounted between said members 5 and 6, the same being adapted to reciprocate in the axial slot 22 formed between the respective members 5 and 6. As shown in the construction illustrated in Fig. 5, said cutter bar has an upwardly projecting obliquely extending hollow-ground double-edged blade element 23 integrally formed thereon, which 55 blade reciprocates longitudinally in the oblique

slot 24 formed between the shearing members 7 and 8. Said cutter bar is provided with a central, transversely-extending slot 25 which is adapted to snugly receive a cam wheel 26 that is mounted on a pin 27, which latter is in turn eccentrically mounted on the upper end of the shaft 2.

In the construction shown in Fig. 7, the reciprocating cutter bar 30 has a replaceable blade element which is detachably but rigidly held therein by a set screw 31, said blade element comprising a flat thin metal shank 32 on which is mounted a hollow-ground double-edged blade member 33. Said bar also has a transverse slot 34 for the reception of the cam wheel 26.

In the construction shown in Fig. 8, the cutter bar 35 is generally similar to the cutter bar 20, except that the blade element 36 thereof is of lesser height and the shearing edges of the shearing members 37 and 38 slightly overlap the adjacent shearing edge of the blade element when such edge is in its closest proximity thereto during the shaving operation.

In the modified construction illustrated in Figs. 9 to 14, the cutter bar 40 reciprocates both laterally and longitudinally in a slot 41 formed between the opposing shearing members 42 and 43 of the shaving head and which slot is parallel to the longitudinal axis of the shaving head. On the bottom of said bar is provided a transverse slot 44 for the reception of the cam wheel 26 and oblique slots 45 for the reception of rollers 46 that are mounted on pins 47 rigidly anchored in the member 43. The cutter bar in this construction constitutes a blade carrier, the same being provided with spaced vertical pins 48 which are adapted to be projected through registering apertures 49 formed in a double-edged blade element 50 and having a central aperture 51 for the reception of a screw 52 that is adapted to be threaded into said blade element. The height of the cutter bar 40 is such that at the extreme limit of the lateral movements of the blade carrier and blade mounted thereon the ground faces of members 42 and 43 adjacent their shearing edge will be overlapped by the ground bottom faces of the blade adjacent the shearing edges *f*, *f'* thereof. As a consequence, the blades during their reciprocation in the slot 41 are actually sharpened due to the sliding frictional engagement of their ground lower faces and the said upper ground faces of the members 42 and 43. Furthermore, such construction prevents the possibility, in the event of wear of the moving parts of the implement, that the shearing edges *f*, *f'* of the blades will forcibly strike against the shearing edges *e*, *e'* of the shearing members 42 and 43 and become dulled or blunted as a result of such forcible engagement therebetween.

Preferably, as shown in Figs. 10 and 14, the shearing edges *f*, *f'* of the blade, while parallel to each other, extend on the bias, i. e. at an acute angle, with respect to the shearing edges *e*, *e'* of the members 42 and 43, which latter edges are parallel to each other and extend normal to the transverse axis of the shaving head. Consequently, any hairs projecting into the slot 41 will be successively sheared off during the shaving operation due to the fact that the co-operating shearing edges of the blade and of the associated shearing members being relatively oblique with respect to each other, function as true shears and relatively cross each other progressively of their length.

In the operation of the implement of the form illustrated in Fig. 1, the anti-clockwise rotation of the shaft will through the associated cam wheel and the co-operating slot 23 in the cutter bar, effect the longitudinal reciprocation of the cutter bar in a direction parallel to the longitudinal axis of the shaving head. Since the shearing edges of the shaving head members 5 and 6, though parallel to each other, extend obliquely with respect to the longitudinal axis of the shaving head, the mouths of the slot 24 on the respective sides of the blade will be respectively, alternately opened and almost but not absolutely completely closed during the longitudinal reciprocation of the cutter bar axially in the shaving head, with the consequence that hairs entering the slot 24 first through the open mouth thereof on one side and then through the open mouth in the other side thereof will, as the said slots alternately substantially but not absolutely close, be sheared off substantially flush with the surface of the skin of the person shaving with my improved dry shaver. As is apparent from the construction illustrated in Figs. 1 and 2, the implement is so designed that the co-operative shearing edge on one member of the shaving head and the adjacent edge of the movable blade will at no time actually forcibly impinge against each other but they are designed to so closely approach each other as to shear off all hairs entering therebetween into the slot 24. However, in the construction shown in Fig. 8, the edges of the blade are just below the level of the shearing edges of the shaving head and consequently the mouths of slot 24 on either side of the blade will be completely closed during the reciprocation of the blade.

While I prefer to employ a double-edge blade member, my invention as embraced within the scope of the appended claims, also contemplates the use of a single-edged blade, in which event, of course, only the adjacent edge of the groove in the shaving head would be lapped or sharpened to a shearing edge. Furthermore, while I prefer to sharpen the edges of the slot in the shaving head to a razor-like edge, this is not essential, since the reciprocating blade member will force the hairs against the adjacent edge of the slot and then the shearing edge of the blade member will of itself effect the severing of the hairs so held by the edge of the slot even though the latter is relatively dull. Various other changes in the details of construction, also within the scope of the appended claims, may likewise be made.

In addition to the advantages hereinbefore mentioned, may be mentioned the fact that due to the fact the blade member is adapted to directly contact with the face, it is possible by exerting a little extra pressure on the razor shaving head when shaving therewith, to press the blade over substantially its entire surface against the skin and such pressure being imparted through the cam and shaft to the motor immediately slows down the motor with the result that the reciprocation of the blade member is correspondingly slowed down and the hairs have a longer period in which to enter the receiving slots. Accordingly, the user can thereby to a certain extent regulate the motor speed as well within reasonable limit, whereas were there an intermediate guard or plate or comb interposed between the blade and the face of the user, such action would not be possible.

Having thus described my invention, what I

claim and desire to obtain by United States Letters Patent is:

In a shaving implement, the combination comprising a stationary shaving head having a longitudinal slot formed therein and extending through the top wall thereof whose outer opposing marginal edges comprise shearing edges, a movable cutter bar member mounted in said slot and means, including a plurality of rollers, mounted on one of said members, and a plurality of co-operating transversely oblique grooves,

5 formed in the other of said members, for effecting reciprocation of the cutter bar obliquely with respect to the longitudinal axis of the slot in the shaving head, whereby the longitudinal edges of the cutter bar during the reciprocation thereof approach and then recede from the adjacent shearing edges of the shaving head thus alternating forming hair-receiving slots on either side of the cutter bar during the movements thereof.

JAMES D. ALTEMUS.
